UNITED STATES PATENT OFFICE.

FRANK C. THORNTON, OF EAST CLEVELAND, OHIO.

METAL-CONTAINER SEALING-CLOSURE-FASTENING APPARATUS.

Application filed July 19, 1926. Serial No. 123,560.

This invention relates to new and useful improvements in sheet metal container sealing closure fastening apparatus providing means for rapidly and easily fastening the sealing closure or cover on a sheet metal container of the type having an air and liquid tight compressed gasket seal and double friction seal.

A further object of the invention is to fasten the sealing closure on a container in a manner to allow the cover to be easily and quickly removed without undue distortion by convenient means detachably secured to the container side permitting the cover to be re-applied to the container by the fastening apparatus.

Other objects and features of the invention will be hereinafter pointed out and described.

In the drawings:—

Fig. 1 is a vertical sectional view of the sealing apparatus on line 1—1 of Fig. 3 showing the clamping sectors in normal open position and applied to a sealing closure on a container partly shown.

Fig. 2 is a similar view showing the sectors closed in fastening position on the closure and container.

Fig. 3 is a sectional view on line 3—3 of Fig. 1.

Fig. 4 is a detail plan view of a clamping sector.

Fig. 5 is a bottom view of the fastening apparatus.

Fig. 6 is a bottom view of a clamping sector.

Fig. 7 is a fragmentary view in elevation looking in the direction of the arrows 7—7 of Fig. 1.

Fig. 8 is a sectional view on line 8—8 of Fig. 1.

Fig. 9 is an elevation of a sealed container and closure showing a closure removing lever detachably secured to the container side.

Fig. 10 is a plan view of a sealed container and closure.

Fig. 11 is an enlarged detail sectional view through the container mouth bead showing the sealing closure fastened thereon in full lines and in dot and dash lines positioned above the container. A closure removing lever is shown in dotted lines applied to the fastened closure for removal thereof.

Fig. 12 is a perspective of the closure removing lever.

Referring to the fastening apparatus shown in the drawings, 4 indicates a base member comprising a ring 5 having an outer depending flange 6 with a peripheral face 7. The base ring 5 is integrally formed with webs 8 and a central hub 9 having the stud 12 of a post 11 threaded therein as at 10. The post 11 has an enlarged annular shoulder 13 seating on the hub top and a further enlarged flange portion 14 spaced from the hub top. The upper end of post 10 has flat side portions 15 and a pin opening 16 for purposes to be hereinafter described.

A plurality of sector shaped sealing closure clamping members 17 are mounted and slidable radially to and from the post 11 on the top of base 4 over webs 8. Each clamping sector 17 has an outer arc-shaped depending flange 18 with an inner arc-shaped wall 19 and an arcuate flange 20 extending inwardly from flange 18. The arcuate flange 20 has a beveled top surface 21 and an inner arc-shaped wall 22 slightly rounded at the intersection with beveled surface 21 as at 23. The wall 19 is slightly rounded at the top and bottom thereof and the flange 18 is beveled outwardly at the bottom. The sector has a reduced body 24 extending toward the post, terminating in an arc-shaped end 25 disposed under the post flange 14 and slidably retained thereby. An elongated guide slot 26, disposed in each sector on the middle line thereof, has upper guide walls 27 with lower relieved sides 28 and top raised parallel slideways 29. Spaced ears 30 having pin openings 31 are disposed at the inner ends of the slideways 29.

Each sector 17 is radially guided in relation to the post center and retained on base 4 by a guide block 32 secured on the base 4 by screws 33. As shown in Figs. 1, 2 and 8 the guide blocks 32 have guide sides 34 slidably engaging the sector slot sides 27 and 100 an enlarged top 35 slidably engaging the sector slideways 29. The outer block ends are extended slightly and have an integral ear 36 thereon with a pin opening 37. A stop pin 38 is mounted on the top of the 105 block.

Each sector 17 is actuated through a toggle comprising a pair of links 39 pinned as at 40 to the fixed block ear 36, and a link 41 pinned as at 42 to the sector ear 30. The 110

links 39 and 41 are of equal length and are connected together by a pin 42 to depending links 43 having their upper ends pinned as at 44 to the arms 47 of a spider carriage 5 46 slidably mounted on post 11 as at 48.

The spider carriage 46 is supported at opposite sides of post 10 by legs 53 and helical compression springs 52 seated on the shoulders of the reduced leg extensions 54 10 extending through the springs 52 which are received in vertical openings 50 in side extensions 49 of the spider casting. The tops of the openings 50 have shoulders 51 for seating the spider on the springs 52. The 15 legs 53 set on post flange 14.

As shown in Figs. 1 and 3 the springs 52 and legs 53 normally hold the spider carriage 46 in raised or inoperative position, the links 43 lifting link 41 against link 39 20 holding the sector arcuate flanges 18 and 20 outwardly from ring flange 6.

Means for contracting the clamping sectors, by depressing the spider carriage and links 43, 39 and 41, comprises oppositely arranged eccentric cams 56 and 57 engaging a heavy washer 55 about post 11 seated on the top of the spider carriage 46. Each eccentric cam 56 and 57 comprises a web 58 formed integrally with an annular cam face 30 59 having a flat face 60 and a pin boss 61 located adjacent thereto eccentric with the annular cam face 59. A lever arm 63 is screw threaded into a boss 64 in the cam and is aligned radially to the center of the annular cam face 59 and at approximately 45° to the flat face 60. The cams are mounted on a pin 65 secured by cotters 66 in post hole 16 and are arranged on opposite sides of post 11 with the webs 58 positioned and 35 adjacent to the post flat sides 15. The compression springs 52 force the spider carriage 46 and washer 55 upward against the cams normally turning the flat face 60 into engagement with the washer 55 maintaining 40 the lever arms 63 upward in Y-shaped relation when in inoperative position.

A hand grip 64 provided for carrying the apparatus and applying to container closures for fastening, is mounted in a yoke 65 secured to the top of post 11 by a bolt 66 and lock nut 67.

A type of sheet metal container with sealing closure, to be fastened thereon air and liquid tight with a compressed gasket seal 55 and double friction seals by the fastening apparatus, comprises a sheet metal container 70 having an annular body wall 71 formed with an outwardly extending mouth flange 72, an upwardly extending annular wall 73 60 with an inwardly rolled annular bead 74. The container bottom is indicated at 71' and the bail at 70'. The cover closure 75 of sheet metal has an upstanding annular wall 76 with an outwardly extending flange 77 and 65 a substantially half round annular bead 78

having spaced depending fastening fingers 79. An annular rubber gasket 80 of preferably tubular cross section is carried on wall 76 under flange 77.

In operation to fasten a sealing closure 70 on a container, the closure is first placed on the mouth of the filled container and the fastening apparatus is lifted by its handle 64 and positioned on the closure 75 as shown in Fig. 1 with the periphery 7 of the base ring flange 6 fitting and centering within closure annular wall 76 and the flange base setting on the closure. The bottom sides of the sectors 11 set on the top of the closure bead 78. The cam levers 63 are then forced downward by the operator to the position shown in Fig. 2, the eccentric cams 56 and 57 forcing the washer 55 and carriage 46 downward on post 11, and against springs 52. The links 43 move downward carrying links 39 into engagement with the top of stop posts 38. The links 41 are moved downward and inward against ears 30 forcing and contracting the clamping sectors 17 inwardly towards post shoulders 13.

The sector arcuate flange walls 22 with rounded tops 23 when drawn inwardly first engage and bend the closure fingers 79 inwardly. The beveled walls 21 moving inwardly next act, bending and forcing the fingers under the container flange 72 simultaneously coacting with sector walls 19 and base ring wall 7, forcing the closure bead 78 downward tightly around the container bead 74 providing a friction seal between the beads for the closure. The fingers 79 are bent at an angle substantially the same as the beveled walls 21 having a space between the inner finger ends and the container flange for purposes to be hereinafter described. The squeezing or clamping action of the contracting beveled walls 21 on bead 78 and the downward thrust of flange 6 on closure top 75' also forces the closure 100 annular wall 76 into a press fit with the container annular mouth wall 71 providing another friction seal between for the closure. Simultaneously the tubular rubber gasket 80 is compressed between closure and container flanges 77 and 72 providing another closure seal. The downward pressure applied on the levers 63 against springs 52 is distributed on the top of closure bead 78 and the closure top 75' co-operating with 110 the beveled walls 21 in effecting tight closure friction seals. The rim 6 of the head forms an abutment for the inward pressure of the contracting members and prevents distortion 115 of the container mouth.

After fastening the sealing closure on the container, the cam lever arms 63 are released allowing the springs 52 to return the fastening apparatus parts to their initial position as shown in Fig. 1, elevating the car- 120

riage 46 and cam lever arms and expanding the sectors 24 permitting the apparatus to be lifted by the handle 64 off the sealed container.

- 5 Means for opening the sealed container is provided by a lever 81 having a hooked end 82. The opposite end is notched oppositely as at 83 providing an end tab 85, the notch sides of the lever portion tapering 10 nearly to a point as at 84. The tab 85 is suitably secured by spot welding or other means to the container at a convenient position for shipping. When desired to open the container, the lever 81 is lifted breaking 15 away from the tab 85 at the point 84. The hooked lever end 82 is positioned over the spaced closure finger end as shown in dotted lines in Fig. 11 and the lever is pushed upwardly bending the closure fastening finger 20 79 downward allowing the closure 75 to be lifted off the container 70 as shown in dot and dash lines. The closure may be used over again for sealing the container without reshaping. If the ends of the fastening fingers 79 are bent against the bottom of container flange 72 the pointed lever end 84 may be inserted between, bending the fingers enough for application of the hooked lever end 82.
- 39 While I have shown and described one embodiment of the invention, obviously various changes in the proportions and details of construction may be made without departing from the scope and spirit of the appended claims.

I claim:

1. In a machine for applying a sheet metal closure to a container having a projecting bead at the top, the combination of a head 40 adapted to rest upon said closure within said rim, a set of radially movable bending members mounted upon said head and having depending hook-shaped flanges at their outer ends adapted to be contracted and 45 bend the edge of the closure under said rim, a post standing on the head, a lever pivoted on the post, and operating connections between the lever and said members adapted to contract said members inwardly and simultaneously press downwardly on the closure 50 when pressure is applied to the lever.
2. In a machine for applying a closure to a container having a projecting rim, the combination of a head adapted to fit upon 55 said closure within said rim, a central post mounted on the head, a set of radial bending members having hooked flanges at their outer ends, guides on the head for said members, a sleeve slideable up and down on the post, 60 toggle connections between the sleeve and said members to shift the latter inwardly, a spring tending to lift the sleeve and ex-

pand the members, and a lever fulcrumed on the post and bearing on the sleeve and adapted to depress the latter and shift said 65 members inwardly to bend the edge of the closure under the rim when pressure is applied to the lever.

3. In a machine for applying a closure to a container having a projecting rim or bead, 70 the combination of a head adapted to rest upon said closure within the bead, a set of radially movable members, having hooked depending flanges at their outer ends between which and the edge of the head the 75 bead and the edge of the closure may be received, and pressure actuated means mounted on the head to shift said members inwardly and thereby bend the edge of the closure under the bead, and means to return said members to expanded position, the 80 means to contract the members including toggles connected together and levers pivotally mounted on the head and operatively connected to said toggles. 85

4. In a machine for applying a closure to a container having a projecting rim, the combination of a head adapted to fit upon the closure, a central post mounted on the head, having a projecting shoulder, a set of 90 radially movable members having their inner ends confined under the shoulder and hook-shaped bending flanges at their outer ends adapted to bend the edge of the closure under said rim, a sliding sleeve on the post, 95 toggle connections between the sleeve and said members, a spring tending to lift the sleeve to expand said members, and a lever fulcrumed on the top of the post and pressing on the sleeve and adapted when depressed to lower the sleeve and contract said members. 100

5. In a machine for applying a closure to a container having a projecting rim, the combination of a head adapted to fit upon 105 the closure, a central post mounted on the head, having a projecting shoulder, a set of radially movable members having their inner ends confined under the shoulder and hook-shaped bending flanges at their outer 110 ends adapted to bend the edge of the closure under said rim, a sliding sleeve on the post, toggle connections between the sleeve and said members, a spring tending to lift the sleeve to expand said members, and a lever 115 fulcrumed on the top of the post and pressing on the sleeve and adapted when depressed to lower the sleeve and contract said members, the post having a handle at the top to hold the machine in position on the closure. 120

In testimony whereof, I do affix my signature.

FRANK C. THORNTON.
